RESETTABLE REGISTER

Application filed December 18, 1928. Serial No. 326,846.

My invention relates to counting devices and more particularly to resettable registers.

While the invention is adaptable for many uses, the illustrated embodiment was especially designed for use in a postal metered mail machine such as the machine shown in my co-pending application, Serial No. 312,900, filed October 16, 1928, and will be described in connection with this use.

10 Resettable registers are employed in counting a number of operation or value units and the registering elements are adapted to be set to indicate zero or to some other value after a period of service by the register or 15 after said register has counted a given total of units.

The type of register to which my invention especially relates includes a series of indicia wheels freely rotatable on a shaft and actuated by a series of "carry-over" pinions disposed parallel therewith. In order to reset the indicia wheels readily the drive pinions must be moved out of mesh with these wheels. In order to accomplish this and yet be able 25 to return the pinions into proper mesh with the indicia wheels, it is necessary that the pinions be held in alignment while they are out of mesh with the indicia wheels, and that the latter be restrained so that after they 30 have been reset the gear teeth thereon will be in proper alignment to receive the aligned pinions.

It is an object of my invention to provide an improved resettable register of the type 35 above described.

Further objects and advantages will be made manifest in the following description and accompanying drawings in which

Figure 1 is a transverse sectional view 40 taken on the line 1—1 of Fig. 2.

Fig. 2 is a bottom plan of a preferred embodiment of my invention,

Fig. 3 is a front elevational view of my invention taken in the direction of the arrow 45 3 in Fig. 1.

Fig. 4 is a view of a door embodied in my invention,

Fig. 5 is a fragmentary view similar to Fig. 2 illustrating the parts of the invention 50 in a different position,

Figs. 6 and 7 are diagrammatic cross-sectional views taken on the lines 6—6 and 7—7 of Fig. 3 and illustrating the operation of the invention.

Referring specifically to the drawings and 55 particularly to Figs. 1, 2 and 3, the illustrated embodiment of my invention is included in a control device 4 which is associated with a shaft 5 adapted to be connected to any mechanism such as say a device for printing 60 metered postal indicia, whose performances or cycles of operation it is desired to count and control. The control device 4 includes a casing 6, enclosing a frame 7 upon which is supported an ascending totalizing register 8 which is driven through gearing 9 by the shaft 5. Also mounted on the frame 7 is a descending resettable register 10 which is driven through gears 11 from the shaft 5.

The descending resettable meter 10 includes a series of indicia wheels 12, mounted upon a shaft 13 and a pinion drive mechanism 14. Each of the indicia wheels 12 has a gear 15, a notched disc 16 on one side thereof and a carry-over disc 17 on the other side thereof. Supported on a shaft 18 journaled in the frame 7 opposite the register 10, is a control comb 19, having teeth 20, one of which rests against the outer surface of each of the discs 16. The shaft 18 is provided with means 70 (not shown) for locking the shaft 5 against rotation when the discs 16 are all so positioned that notches 25 therein are aligned opposite the teeth 20 of the comb 19 so that these fingers may be moved into the notches 25 as 75 shown in Fig. 6.

Provided on the shaft 18 is an arm 26 having a pin 27 for a purpose to be described hereafter. Coiled about the shaft 18 is a spring 28 (Fig. 2) which urges the comb teeth 90 20 against the discs 16.

The drive pinion mechanism 14 includes a frame 30 rockably mounted on a shaft 31 which is rigidly secured on the frame 7. The frame 30 includes side arms 32 and 33 (Fig. 95 5) which are connected by a cross bar 34 (Fig. 6) and shafts 35 and 36. Provided on the bar 34 are series of detent springs 37, a head 38 of each of which is disposed opposite one of the gears 15 for a purpose to be described 100

later. Rotatable on the shaft 35 are a series of drive pinions 40, each of these pinions engaging with one of the carry-over discs 17 of a numeral wheel 12 so that for each revolution of this numeral wheel the gear 15 of the next highest numeral wheel will be turned to bring into view a new digit on said next wheel.

Slidably mounted on the shaft 36 is a pair of cam-carrying slides 45 (Figs. 2 and 5) each of which has an upper body portion 46 and depending ends 47 and 48. Coiled about the shaft 36 between the slides 45 is a compression spring 49 which is adapted to hold these slides separated from each other. Extending from the slide ends 48 are finger lugs 50. Also provided on the slide ends 48 are pins 51 which limit the movement of the slides towards each other for a purpose to be described later.

Formed in opposite walls of the frame 7 at opposite points therein are pairs of holes 53 and 54 (Fig. 3). Secured in lower portions of the slide ends 47, and slideable through suitable apertures in the rockable frame arms 32 and 33, are locking pins 55 which are adapted to be urged into either of the pair of holes 53 and 54 by the spring 49. Also provided on the slide ends 47 are cams 58, the purpose of which will be described later.

Swingable on the shaft 36 are short arms 60, free ends of which are connected by a bar 61 extending across adjacent to the pinions 40 and having a series of pinion positioning fingers 62 provided thereon, one of which is disposed opposite each of the pinions 40. In the normal operating position of the resettable register 10, the bar 61 rests upon upper faces of the cams 58 with the jaws 62 out of contact with the pinions 40 (see Fig. 1). Extending downwardly from bar 61 are cam pins 63 (Fig. 6) which are disposed adjacent to cam surfaces 64 of the cams 58.

Extending inward from opposite points on the frame 7 are stops 65 which are adapted to engage the bar 61 to limit downward swinging of the pinion mechanism 14.

Mounted on inner faces of the arms 32 and 33 are leaf springs 66 which bear against the arms 60 and urge these downwardly. The side arm 32 has a rearward extension 70 to which is pivotally connected a link 71 having a slot 72 in its upper end which is adapted to receive the pin 27 on the arm 26.

The casing 7 has a door opening 75 which is adapted to be closed by a door 76 which may be hingedly mounted on the frame 7 as shown in Fig. 1. The door 76 is adapted to be secured in closed position by a suitable lock 77.

The operation of my invention is as follows:

The control device is particularly adapted to be set so that after a given number of revolutions of the shaft 5 this shaft will be locked

against rotation until the door 76 is opened and the descending register 10 re-set. Each time the descending register is re-set, the indicia wheels 12 are arranged so as to indicate the number of rotations which the shaft 5 may make before the device again locks this shaft. The notches 25 are arranged so that this locking occurs when the descending register 10 indicates zero. That is, when zero is indicated by all the indicia wheels 12 the notches 25 are aligned to receive the comb 19 and permit the shaft 18 to turn and thereby lock the shaft 13, as shown in Fig. 6, and consequently the shaft 5.

To reset the descending register 10 and unlock the shaft 5 the proper key must be inserted in the lock 77 and the door 76 opened. The finger lugs 50 are now engaged between the thumb and forefinger and pressed together as shown in Fig. 5 so as to compress the spring 49 and withdraw the locking pins from the holes 53 in the casing 7. This movement also brings the cam surfaces 64 against the pins 63 so as to swing the arms 60 and bar 61 upwardly, as shown in Fig. 6, so that the pinion positioning fingers 62 engage the teeth of pinions 40 and align these pinions while they are still in mesh with the gears 15. It is to be noted that at this time the spring detents 37 are out of engagement with the gears 15 as shown in Fig. 6.

After the finger lugs 50 are moved together as above described, the frame 30 is swung downwardly about the shaft 31 to the position in which it is shown in Fig. 7, which removes the pinions 40 from mesh with the gears 15 and swings the spring detent heads 38 into yieldable engagement with the teeth of these gears. When the drive pinions mechanism 14 is thus positioned, the pins 55 are disposed opposite the lower holes 54 formed in casing 7 so that when the finger lugs 50 are released, these pins are urged into the holes 54 by the spring 49. At this time the finger lugs 50 extend into the door opening 75 (as shown in Fig. 7 by the broken line 90) so that the door 76 cannot be closed until the pinions 14 have been returned to meshing engagement with the gears 15. When the finger lugs 50 are released to permit the pins 55 to extend into the holes 54, the cams 58 no longer support the pinion positioning fingers 62 in aligning engagement with the pinions 40, but these fingers are retained in this position by the stops 65 against which end portions of the bar 61 now rest as shown in Fig. 7.

The indicia wheels 12 are now free to be manually rotated to indicate any desired number of rotations for the shaft 5. Rotation of these wheels is yieldably resisted by the detent springs 37, which keep the wheels 12 in alignment so that pinions 40 may be readily returned into mesh with the gears 15 whenever this is desired. When the wheels 12 have been properly set, the finger lugs 50 are again

gripped so as to pull the pins 55 out of the holes 54 and the pinion mechanism 14 is swung back into the position in which it is shown in Fig. 6 in which the pinions 40 mesh 5 with the gears 15. The pins 55 are now opposite the holes 53 into which these pins extend when the finger lugs 50 are released by the fingers. When the slides 45 are separated by the spring 49 the bar 61 is permitted to swing 10 by gravity directly into its normal position, (as shown in Fig. 1) in which the fingers 62 are out of engagement with the pinions 40. The finger lugs 50 are now disposed out of the door opening 75 so that the door 76 may 15 be closed and locked.

It is to be noted that when the pinion drive mechanism is swung downwardly, as shown in Fig. 7 to free the gears 15 from the pinions 40, the link 71 is moved upwardly so that the 20 bottom of the slot 72 engages the pin 27, swings the shaft 18 to withdraw the fingers 20 from the notches 25 and thereby unlocks the disks 16 and shaft 5. When the indicia wheels 12 have been reset, the notches 25 will 25 not be in alignment so that when the mechanism 14 is swung back into its position with the pinions 40 meshed with the gears 15, certain of the fingers 20 will contact and ride upon the peripheral surface of the discs 16 30 so as to retain the locking mechanism connected to the shaft 18 in non-locking position until the descending register 10 again indicates zero.

It is thus seen that I have provided a control device in which the drive pinions are brought into alignment before they are moved 35 out of mesh with the indicia wheel gears; in which the door may not be closed until the drive pinions have been turned into mesh with these gears; and in which the drive pinions 40 are locked in alignment while they are being moved between meshing and non-meshing positions. It is to be further noted that the same mechanism which aligns the pinions to 45 permit re-setting of the register also yieldably retains the indicia wheels against accidental rotation while the pinions are out of mesh with the indicia wheel gears and releases these wheels when the pinions are 50 again brought into meshing relation with said gears.

It is further noted that my device embodies a control means for the register drive when the pinions are removed from mesh with the 55 indicia wheel gears for resetting the register.

While I have illustrated and described but a single embodiment of my invention it is understood that many modifications might be made in this without departing from the 60 spirit of the invention or the scope of the appended claims.

I claim:

1. A register containing a frame, a shaft, a plurality of indicia wheels and gears there- 65 for carried on said shaft, a carriage mounted

on said frame, a plurality of transfer pinions mounted on said carriage for meshing with said gears respectively, a latch mounted on said carriage and constructed with locking fingers, bolts mounted on said carriage for engaging holes in said frame for locking said carriage in position with said transfer pinions in mesh with said gears, draw bars connected respectively to said bolts, a spring engaging said draw bars for normally holding said draw bars apart and said bolts in engagement with said holes, pins on said latch, cams on said draw bars respectively for engaging said latch pins and moving said locking fingers in locking engagement with said 70 pinions before said carriage is shifted and after said pinions are withdrawn from said gears.

2. In a resettable register, the combination of: a frame; a shaft; a plurality of indicia wheels on said shaft having gears provided thereon; pinions adapted to mesh with said gears and actuate said wheels; a carriage on which said pinions are mounted, said carriage being shiftable on said frame to withdraw said pinions from mesh with said gears to permit said wheels to be reset; means for locking said carriage with said pinions and gears in mesh; means for releasing said locking means to permit shifting said carriage to unmesh said pinions and gears; a pinion latching means actuated by said lock releasing means to latch said pinions against separate rotation when said lock is released; and means automatically preventing said latching means disengaging said pinions until said locking means is relocked.

3. In a resettable register, the combination of: a frame; a shaft; a plurality of indicia wheels on said shaft having gears provided thereon; pinions adapted to mesh with said gears and actuate said wheels; a carriage on which said pinions are mounted, said carriage being shiftable on said frame to withdraw said pinions from mesh with said gears to permit said wheels to be reset; means for locking said carriage with said pinions and gears in mesh; means for releasing said locking means to permit shifting said carriage to unmesh said pinions and gears; a pinion latching means actuated by said lock releasing means to latch said pinions against separate rotation when said lock is released; and means mounted on said carriage which engage said wheel gears to prevent their being moved accidentally while said pinions are out of mesh with said gears, said means disengaging said wheels when said carriage is shifted to return said pinions into mesh with said gears.

4. In a resettable register, the combination of: a frame; a shaft; a plurality of indicia wheels on said shaft having gears provided thereon; pinions adapted to mesh with said gears and actuate said wheels; a carriage on

which said pinions are mounted, said carriage being shiftable on said frame to withdraw said pinions from mesh with said gears to permit said wheels to be reset; means for locking said carriage with said pinions and gears in mesh; means for releasing said locking means to permit shifting said carriage to unmesh said pinions and gears; a pinion latching means actuated by said lock 10 releasing means to latch said pinions against separate rotation when said lock is released; and means mounted on said carriage which engage said wheel gears to prevent their being moved accidentally while said pinions are 15 out of mesh with said gears, said means disengaging said wheels when said carriage is shifted to return said pinions into mesh with said gears; and means automatically preventing said latching means disengaging said 20 pinions until said locking means is relocked.

5. In a resettable register, the combination of: a casing; a door in said casing; a series of indicia wheels mounted in said casing; a series of pinions for actuating said indicia 25 wheels; means separate from said door for supporting said pinions; means for locking said pinions in alignment and moving them out of mesh with said indicia wheels; and means preventing said door being closed before said pinions are returned into mesh with said wheels.

In testimony whereof, I hereunto affix my signature this 13th day of December, 1928.

RALPH G. WHITLOCK.
